[57] ABSTRACT

The pump mounting assembly of this invention comprises a casing assembly and a pump mount. The casing assembly includes a substantially cylindrically shaped, upstandingly disposed casing wall and a casing cap plate selectively lockingly fastened transversely to the uppermost terminal end of the casing wall. The

pump mounting includes a pump flange, a base flange and a filter liner. The pump flange has a suitable configuration to closely slidably engage the interior of the casing wall. The pump flange is dependently carried by means of a yoke connected to a cable fastened between the yoke and the casing cap plate. The pump flange is also fastened to the water discharging conduit of the pump distally from the pump. The pump flange includes venting means controllable from the yoke. The base flange has a substantially ring-like configuration with the outer configuration similar to the interior configuration of the casing wall, and has an interior hole operable to permit passage of the pump. The base flange is fastened to the interior of the casing wall distally from the lowermost terminal end of the casing. The base flange includes bevelled gear-like teeth provided on its uppermost terminal end. The pump flange includes corresponding bevelled gear-like teeth on its lowermost terminal side operable to interlockingly engage the base flange and the pump flange. The filter liner is fastened to the lowermost terminal edge of the base flange, and includes a substantially cylindrical configuration of a smaller diameter than the diameter of the casing wall. The filter liner includes a multiplicity of holes and a shoring means which may include a pair of outwardly urged paddle-like shoring members.

FIG. 1

FIG. 2

DELWIN W. BUTTERFIELD INVENTOR

BY *John W. Butterfield*

PUMP MOUNTING ASSEMBLY

FIELD OF INVENTION

The present invention relates to pump mounting means, and more particularly to mounting means operable to removably mount submersible pumps, vacuum pumps, and the like.

DESCRIPTION OF THE PRIOR ART

Means commonly used and employed to mount submersible pumps, vacuum pumps, and the like, have included means which fasten the pump mechanism to the cap plate of the casing. This means of mounting such pumps necessitates sealing the entire length of the casing. Such pumps are restricted as to the depth of a well in which they may be used because the sealing of very long casing lengths requires complex heavy gasketing and casing connectors to maintain a vacuum. A continual problem, particularly for submersible pumps and vacuum pumps, is providing filter means in deep wells to filter out sand and the like.

Accordingly, it is an object of the present invention to provide mounting means which are operable to permit removal of submersible pumps and vacuum pumps.

It is another object of this invention to provide removable mounting means which are operable to seal the pumping chamber at a point distally below the casing cap plate.

It is a further object of this invention to provide filter means and shoring means at the base of the casing of a well to reduce the amount of particulate matter in the pumping zone.

It is an object of this invention to provide removable pump mounting means and filter and shoring means which will be operable for deep wells.

These and other objects shall become apparent from the description following, it being understood that modifications may be made without affecting the teachings of the invention here set out.

SUMMARY OF THE INVENTION

Generally, the pump mounting assembly of this invention comprises a casing assembly and a pump mount. The casing assembly includes a substantially cylindrically shaped, upstandingly disposed casing wall and a casing cap plate selectively lockingly fastened transversely to the uppermost terminal end of the casing wall. The pump mount includes a pump flange, a base flange and a filter liner. The pump flange has a suitable configuration to closely slidably engage the interior of the casing wall. The pump flange is dependently carried by means of a yoke connected to a cable fastened between the yoke and the casing cap plate. The pump flange is also fastened to the water discharging conduit of the pump distally from the pump. The pump flange includes venting means controllable from the yoke. The base flange has a substantially ring-like configuration with the outer configuration similar to the interior configuration of the casing wall, and has an interior hole operable to permit passage of the pump. The base flange is fastened to the interior of the casing wall distally from the lowermost terminal end of the casing. The base flange includes bevelled gear-like teeth provided on its uppermost terminal end. The pump flange includes corresponding bevelled gear-like

teeth on its lowermost terminal side operable to interlockingly engage the base flange and the pump flange. The filter liner is fastened to the lowermost terminal edge of the base flange, and includes a substantially cylindrical configuration of a smaller diameter than the diameter of the casing wall. The filter liner includes a multiplicity of holes and a shoring means which may include a pair of outwardly urged paddle-like shoring members.

A more thorough and comprehensive understanding may be had from the detailed description of the preferred embodiment when read in connection with the drawings forming a part of this specification.

BRIEF DESCRIPTION OF THE DRAWINGS

FIG. 1 is a cross-sectional side elevational view of the pump mounting assembly of this invention.

FIG. 2 is a side elevational view of the mounting assembly of this invention with the casing cap plate and pump mount partially withdrawn from the casing, and the wall of the filter in fragmentary cross-section for illustrative purposes.

DETAILED DESCRIPTION OF THE PREFERRED EMBODIMENT

Referring now to the drawings, and more particularly to the FIG. 1, the pump mounting assembly of this invention is shown to advantage and identified by the numeral 10. The pump assembly 10 may be conveniently divided into a casing assembly 11 and a pump mount 12. It is intended that the pump mounting assembly 10 of this invention be used in combination with a submersible pump 13, a vacuum pump, or the like.

The casing assembly 11 comprises a casing wall 14 and a casing cap plate 15. The casing wall 14 is substantially cylindrical and is disposed with its rectilinear axis generally vertical. The length of the casing wall 14 is determined by the depth of the well, the wall being coextensive in length with the depth of the well. The uppermost terminal end of the casing wall 14 is closed by a transversely disposed casing cap plate 15. The casing cap plate 15 is selectively lockingly engaged with the uppermost terminal end of the wall 14 by means, such as bolts 16. The cap plate 15 includes suitable passageway for the water-discharging conduit 17 and an exitway 18 for an electrical wire 19. The pump 13 is fastened to the lowermost terminal end of the conduit 17. It is to be understood that the passageway for the conduit 17 and the exitway 18 for the electrical wire 19 include sealing gaskets to close the casing cap plate 15. The casing cap plate 15 is provided with a vent valve means 20 which is selectively operable to permit outside pressure to enter the casing assembly 11. As shown by the FIG. 1, the vent 20 is usually held in a closed position by an urging spring 21 which urges the valve portion 22 of the vent 20 to engage the casing cap plate 15. The casing assembly 11 may be vented by selectively depressing the vent 20.

The pump mount 12 includes a suspension yoke 23, a flange 24, a base flange 25, and a filter liner 26. The pump 13 is generally dependently carried from the cap plate 15 by means of a cable 27 which is fastened to the lowermost terminal side of the cap plate 15 by means of an eye-bolt 28 at the uppermost terminal end of the plate 15 and a yoke 23 at the lowermost terminal end of

the cable 27. The yoke 23 comprises a fixedly mounted stop shaft 29 and a slidably sleeve 30. The stop shaft 29 is fastened on the conduit 17 distally above the pump 13. The stop shaft 29 comprises a shaft portion 29' and a stop portion 29'' which projects outwardly from the uppermost terminal end of the shaft portion 29'. The sleeve 30 is operable to slide over the shaft portion 29' and to be stopped by the projecting portion 29''. The sleeve portion 30 is provided with a pair of shoulders 30' which project outwardly and provide a suitable receiving means for the cable 27. The lower portions of the sleeve 30 include a pair of outwardly projecting bracket members 31 and 32.

The pump flange 24 includes a horizontally disposed plate having a configuration substantially similar to the interior configuration of the interior cylindrical walls of the casing 14. The uppermost terminal side of the flange 24 includes an upstandingly disposed capstan portion 33 which is operable to ride within the bracket portion 31. The capstan 33 is provided at its uppermost terminal end with a stop means 33' which is operable to contact the uppermost terminal side of the bracket 31. The flange 24 includes a vent 34 which is substantially similar to the vent 20 set out above. The stem portion 34' of the vent 34 is provided with a head portion which is operable to engage the bracket 32. When the casing cap plate 15 is removed from the casing 14, the cable 27 causes the sleeve 30 to ride upwardly on the stop shaft 29; and, simultaneously, causes the brackets 31 and 32 to release air into the portions of the casing assembly 11 below the flange 24, then to engage the head portion of the capstan 33, and to raise the pump flange 24, as shown by the FIG. 2. In a like manner to the plate 15, the flange 24 includes a passageway for the conduit 17, and a sealed exitway 18' for the electrical wire 19. The flange 24 is fastened to the conduit 17 distally above the pump 13.

Referring to the FIGS. 1 and 2, the pump flange 24 is engageable with a fixedly mounted base flange 25. The base flange 25 has a substantially ring-like configuration in which the outer circumference of the flange 25 is substantially identical to the interior configuration of the cylindrical walls of the casing 14. The interior hole 45 of the flange 25 is operable to permit the pump 13 to pass freely through the flange 25. The flange 25 is fastened distally above the lowermost terminal end of the casing 14. The flange 24 and the flange 25 are engageable by means of bevelled gear-like teeth 24' and 50' provided on the lowermost terminal side of the flange 24 and on the uppermost terminal side of the flange 25, respectively. In operation, the pump 13 is dropped through the center hole of the flange 25 and the bevelled portions of the teeth 24 tend to cam with 55 the bevelled portion of the teeth of the flange 25 until the flanges 24 and 25 are in close engagement, as shown more clearly in the FIG. 1. The low pressure region below the flange 24, which tends to be created by the operation of the pump 13, tends to draw the flanges 24 and 25 together more tightly. It has been found to advantage to provide a resilient gasket means 34 in the corner formed by the interior side of the casing wall 14 and the uppermost terminal side of the flange 24.

The filter liner 26 includes a cylinder fastened to the lowermost terminal side of the flange 25, and projects distally below the lowermost terminal end of the casing

wall 14. The outer diameter of the liner 24 is distally smaller than the interior diameter of the casing wall 14. The liner 26 is provided with a multiplicity of holes 36. In operation, water tends to percolate upwardly between the casing 14 and the outer terminal side of the liner 26 and into the holes 36. By this method, sand, silts, and the like, tend to settle and be filtered out. As shown by the FIG. 1, it has also been found to advantage to include foot-like shoring means 37. The shoring means 37 may include a pair of foot-like members 37' projecting downwardly in scissor-like fashion out of the lowermost terminal end of the liner 26 on a pivoting axle 38 disposed transversely distally from the lowermost terminal end of the liner 26. The shoring members 37 may be provided at their lowermost terminal ends with broad paddle-like means operable to press against the surrounding soil to maintain the well structure. In operation, the liner 26, carried by the flange 25, may be forced downwardly through the casing 14 to a predetermined depth. When the shoring means 37 and the liner 26 have been projected sufficiently out of the lowermost terminal end of the casing wall 14, the shoring members 37 are forced outwardly 25 against the soil of the well.

Having thus described in detail a preferred apparatus which embodies the concepts and principles of the invention and which accomplishes the various objects, purposes and aims thereof, it is to be appreciated and 30 will be apparent to those skilled in the art that many physical changes could be made in the apparatus without altering the inventive concepts and principles embodied therein. Hence, it is intended that the scope of the invention be limited only to the extent indicated in the appended claims.

I claim:

1. An apparatus operable to removably mount submersible pumps and the like, comprising
a pump having an inlet and a water discharging conduit;
a casing assembly including a substantially cylindrically shaped, upstandingly disposed casing wall and a casing cap plate selectively lockingly fastened transversely to the uppermost terminal end of said casing wall; and
a pump mount including a pump flange dependently carried by means of a yoke connected to a cable fastened between said yoke and said casing cap plate, said pump flange closely slidably engaging the interior terminal walls of said casing walls, said pump flange being fastened to the water-discharging conduit of said pump distally from said pump, said pump flange having venting means including a valve having a valve stem, said venting means being controllable from said yoke, said base flange having a substantially ring-like configuration with an outer configuration similar to the interior configuration of said casing wall and an interior hole operable to permit passage of said pump, said base flange being fastened to the interior of said casing wall distally from the lowermost terminal end of said casing wall, said base flange having bevelled gear-like teeth provided on its uppermost terminal side, said pump flange having corresponding bevelled gear-like teeth on its lowermost terminal side operable to interlockingly engage said base flange.

flange and said pump flange, said pump mount including a filter liner, said filter liner having a cylindrical configuration of a smaller diameter than the diameter of said casing wall, said filter liner being disposed within said casing wall and being fastened to the lowermost terminal edge of said base flange, said filter liner having a multiplicity of holes, said filter liner having shoring means including a pair of outwardly urged paddle-like shoring members.

2. The apparatus of claim 1, wherein said yoke includes a fixedly mounted stop shaft portion fastened on

said conduit and a slidable sleeve portion operable to ride about said stop shaft, said stop shaft having a shaft portion disposed about said conduit and a stop portion fastened at the uppermost terminal end of said stop shaft, said sleeve portion having outwardly projecting portions operable to engage and retain said cable, said sleeve portion having an outwardly projecting bracket member operable to engage the valve stem of said vent means.
